BOAT

Edwin Farnham Butler, Mount Desert, and Cyrus Hamlin, Southwest Harbor, Maine

Application August 2, 1952, Serial No. 20,886

Term of patent 14 years

(Cl. D71—1)

To all whom it may concern:

Be it known that we, Edwin Farnham Butler and Cyrus Hamlin, both citizens of the United States of America, residing, respectively, at Mount Desert, in the county of Hancock and State of Maine, and Southwest Harbor, in the county of Hancock and State of Maine, have invented a new, original, and ornamental Design for a Boat, of which the following is a specification, reference being had to the accompanying drawing, forming part thereof.

In the drawing:

Fig. 1 is a perspective view of a boat embodying our new design;

Fig. 2 is a top plan view thereof; and

Fig. 3 is a side elevational view thereof.

We claim:

The ornamental design for a boat, substantially as shown and described.

**E. FARNHAM BUTLER.
CYRUS HAMLIN.**
